UNITED STATES PATENT OFFICE

159,685

PIN OR SIMILAR ARTICLE

Raymonde Semensohn, Brooklyn, N. Y.

Application November 25, 1949, Serial No. 6,246

Term of patent 3½ years

(Cl. D45—19)

To all whom it may concern:

Be it known that I, Raymonde Semensohn, a citizen of France, residing in New York city, in the county of Kings and State of New York, have invented a new, original, and ornamental Design for a Pin or Similar Article, of which the following is a specification, reference being had to the accompanying drawing, forming part thereof.

Fig. 1 is a front elevational view of a pin or similar article showing my design, and

Fig. 2 is the side view thereof.

I claim:

The ornamental design for a pin or similar article, substantially as shown.

RAYMONDE SEMENSOHN.
